UNITED STATES PATENT OFFICE.

ROBERT L. AMBROSE, OF TARRYTOWN, NEW YORK, ASSIGNOR TO RAND DRILL COMPANY, OF NEW YORK, N. Y.

VALVELESS ROCK-DRILL.

SPECIFICATION forming part of Letters Patent No. 681,428, dated August 27, 1901.

Application filed November 15, 1900. Serial No. 36,633. (No model.)

To all whom it may concern:

Be it known that I, ROBERT L. AMBROSE, a citizen of the United States of America, residing at Tarrytown, in the county of Westchester and State of New York, have invented certain new and useful Improvements in Valveless Rock-Drills, of which the following is a specification, reference being had to the accompanying drawings, forming a part thereof.

My invention relates to valveless rock-drills; and it consists in the combination, with a cylinder having separate admission and exhaust ports for each end thereof and a common inlet-port, of a piston having a reduced central portion and adapted to control the said ports, the said ports having certain definite relations with respect to each other and to the piston, as shall hereinafter be more fully set forth; and the objects of my invention are to improve and simplify the construction of rock-drills and to so locate the aforesaid ports with respect to each other and to the piston as to give the greatest efficiency and economy of motive fluid in operation.

I will now proceed to describe a valveless rock-drill embodying my invention and will then point out the novel features in claims.

In the drawings, Figure 1 is a central longitudinal section of a valveless rock-drill embodying my invention. Figs. 2, 3, 4, and 5 are diagrammatic views illustrating certain portions of my improved rock-drill and showing the relationship of certain parts in their various positions.

The rock-drill comprises a cylinder, (designated by the reference character *a*.) A piston *b* is mounted to reciprocate within the cylinder, and the said piston may be provided with the usual piston-rod *c*, to which may be secured the ordinary form of drill chuck or head, as may be desired. Lower and upper heads *d* and *e* are provided, which may be of the usual or any desired form, and suitable rotating mechanism *f* may be carried in the upper cylinder-head, as is usual in this type of drill. The cylinder may be mounted upon the usual shell *g*, and feeding mechanism may be provided.

Further detail description of the parts *c*, *d*, *e*, *f*, and *g* is unnecessary, as these parts form no portion of my present invention, all of

which lies in the combination of the piston with the cylinder and the location of the ports in the said cylinder with their relationship to each other and to the piston. Of these ports 55 there is a separate admission-port for each end of the cylinder and a common inlet-port. The admission-port for the forward end of the cylinder is designated by the reference character *h*. The admission-port for the rear end 60 of the cylinder is designated by the reference character *i*. The exhaust-port for the forward end of the cylinder is designated by the reference character *j* and for the rear end of the cylinder by the reference character *k*. I 65 have shown the exhaust-ports *j* and *k* as opening in the side of the cylinder and communicating directly with the atmosphere for purposes of clearness of illustration. In practice these ports may open into a chamber, or 70 pipe connections may be made thereto, all in a manner well known.

The common inlet-port is designated by the reference character *l*, and the said inlet-port is arranged to communicate with an annular 75 channel *m* around the interior of the cylinder.

The piston *b* has a reduced central portion *n*, which terminates in a shoulder *o* toward the forward end of the piston and a shoulder 80 *p* toward the rear end of the piston. The admission and exhaust ports are controlled by the forward and rear ends of the piston and by the shoulders *o* *p* thereof in its movement. With the piston in the position in which it 85 is shown in Figs. 1 and 5 the admission-port *i* to the rear end of the cylinder is open to the inlet-port *l* through the inlet-chamber *m*, while the admission-port *h* at the forward end of the cylinder is closed to the inlet-port *l* by 90 the fact that the forward end of the piston overlies that portion of the cylinder which is between the said admission-port *h* and the inlet-chamber *m*. The exhaust-port *j* at the forward end of the cylinder is open to atmosphere, while the exhaust-port *k* at the rear end of the cylinder is closed by the rear portion of the piston *b*, which overlies same. The piston *b* is shown at the extreme end of a stroke 95 in the rearward direction, and in such position it will be seen that although the admission-port *i* is open to the inlet-port *l* the rear 100

end of the said port *i* (at which point the said port communicates with the rear end of the cylinder) has been overridden by the piston, and is hence closed thereby. The piston in 5 the last part of its movement, however—that is to say, in that portion of its movement after it has overridden the end of the said port—will compress the motive fluid, which is now locked in the end of the cylinder 10 against escape, and the same will act as a cushion to such final movement. Further, by its expansive force it will start the piston on its return movement until the rear end of the said port *i* shall be uncovered by the piston. Motive fluid then passing through the 15 inlet-port *l*, channel *m*, and admission-port *i* will enter the rear end of the cylinder and will continue to force the piston forward until the shoulder *p* thereon overrides the forward 20 end of the admission-port *i*. Motive fluid will then be cut off. During all the movement of the piston up to this point the exhaust-port *j* at the forward end of the cylinder will have been open, and the forward 25 end of the cylinder will thus have been open free to exhaust. At the moment that the shoulder *p* cuts off admission to the rear end of the cylinder by overriding the forward end of the port *i* the forward end of the piston *b* 30 will have overridden the exhaust-port *j* at the forward end of the cylinder, and further movement of the piston will be due to the expansion of the motive fluid which is locked in the rear end of the cylinder, such movement 35 of the piston continuing under the influence of such expansion until the rear end of the piston reaches such a point as to open the exhaust-port *k* at the rear end of the cylinder to atmosphere. I have found that such 40 distance of travel should be equal to about one-fifth of the entire stroke of the piston, and I have also found that most efficient and economical results have been obtained by providing also that this expansion period 45 should take place while and only while both ends of the cylinder are closed to both admission and exhaust. An examination of the diagrams of Figs. 3 and 4 will clearly illustrate that the arrangements of ports herein 50 shown effects this result. At the moment the piston arrives at such a point as to open the rear end of the cylinder to exhaust through the exhaust-port *k* the shoulder *o* of the said piston will have reached a point where it will place in communication 55 the admission-port *h* at the forward end of the cylinder with the inlet-port *l* through the reduced central portion of the piston and the inlet-channel *m*. (See Fig. 3.) Further movement of the piston will be due to its own momentum, and all of the further movement will be against the full pressure of the motive fluid. The proportions of the parts and the location of the ports with respect to each other 60 and to the piston are such that the piston will continue to advance, owing to the great momentum that it has acquired until it is

stopped by the drill-rod, which it carries, coming in contact with a portion of rock upon which it is being operated, or until the piston itself is otherwise stopped mechanically. When the piston *b* has lost its acquired momentum, the motive fluid which is admitted at the forward end of the cylinder through the admission-port *h* will operate to force the piston rearwardly. It will be noted, however, that the point of admission cut-off with respect to a full stroke of the piston is very much earlier in the rearward movement of the piston than in the forward movement. 70 In practice I have found that the correct proportion is about as one is to two. When the motive fluid has been cut off by the shoulder *o* overriding the rear end of the admission-port *h*, the following portion of the rearward stroke 75 of the piston will be due to the expansive quality of the motive fluid which is locked in the forward end of the cylinder. At the moment the admission cut-off at the forward end of the cylinder was effected by the piston the 80 exhaust at the rear end of the cylinder was also effected, and thus, as in the forward stroke, this expansion period of the rearward stroke is effected while both ends of the cylinder are closed to both admission and exhaust. The last portion of the rearward movement will, as in the forward movement, 85 be due to momentum, but in the rearward movement it is not desired to strike a blow, and hence provision must be made for absorbing the momentum within the rock-drill 90 itself. It is of course very undesirable that the piston should strike against the rear head of the cylinder, for the reason that if such were permitted it would be very likely to 95 burst the bolts which hold the rear cylinder-head in position, and failing that would be likely to damage the rotating mechanism which is generally carried in the rear head. I have hence arranged the admission cut-off 100 very much earlier in a stroke in the rearward direction than in a stroke in the forward direction, and I have provided that the last portion of the movement of a stroke in the rearward direction shall be against motive 105 fluid which is locked against exhaust in the rear end of the cylinder and which thus forms a powerful cushion. In the proportions shown herein the cushion is sufficient to prevent the piston from striking the rear head 110 while at the same time it is not sufficient to prevent a substantially full stroke of the piston. This latter is important, for the reason that if the movement of the piston is reversed before it has reached the end of its 115 stroke the downward stroke of the piston will lose much of its effective force. 120

I am aware that valveless rock-drills have been experimented with for many years and that a number of patents have been granted 130 upon them; but these rock-drills have all been defective because of the incorrect relationship of the ports with respect to each other and to the piston. I have found that

a certain definite relationship of the ports with respect to each other and to the piston is absolutely necessary for efficient and economical results, and such relationship of ports

5 I have herein shown, described, and pointed out in claims.

In the drill which I have successfully operated and from which the drawings forming a part of this specification have been made

10 I have proportionated the parts and arranged the ports about as follows.

I have arranged that a full stroke of the piston shall consist of a travel of five and three-quarter inches, that upon a rearward

15 stroke admission cut-off shall take place after a movement of one and five-eighths inches, that during all of this movement the rear end of the cylinder shall be open and free to exhaust, that the following movement of one

20 and one-eighth inches shall be a period of expansion and that the said period of expansion shall take place with the cylinder closed at both ends to both admission and exhaust, and that the remaining three inches

25 of movement shall be against the pressure of motive fluid at the rear end and with the forward end of the cylinder open to exhaust. With these proportions it will be seen that admission cut-off and release at the forward

30 end are respectively simultaneous with exhaust closure and admission at the rear end, but are very much earlier in a rearward stroke than in a forward stroke. It will also be seen that the expansion of the working

35 fluid at either end is while and only while the other end is closed to both admission and exhaust, and further that this expansion period takes place very much earlier in the rearward stroke than in the forward stroke.

40 It is very essential that in the early portion of the rearward stroke of the piston there shall be a high lifting power, for the reason that in rock-drilling the drill often becomes more or less jammed in the hole and requires

45 considerable force to start it out. Once started the power required to continue the movement is very much less, and, as before explained, in the latter part of the rearward stroke the movement of the piston needs to

50 be heavily cushioned. In my arrangement of parts and location of ports I have provided great lifting power for the piston in the first portion of the return or rearward stroke thereof. I have then quickly cut off the ad-

55 mission of the motive fluid and have used the same expansively for the next portion of the stroke, and have thus obtained an effective power, coupled with economy of working.

Lastly, I have provided a cushion at the rear

60 end of such quality as to correctly balance the force of momentum acquired.

In operation the expansion of the motive fluid takes place while and only while both ends of the cylinder are closed to both ad-

65 mission and exhaust. I have in this arrangement not only obtained a high efficiency in

work, but a great economy of motive fluid. While so working expansively at one end of the cylinder by closing the other end to both admission and exhaust I obtain a small ini-

70

tial pressure of the motive fluid, which is locked in the other end. Such amount is not sufficient to seriously check the piston in its movement, the slight tendency to check the

75

same being rather beneficial than otherwise. When the admission is opened in the continuance of the movement of the piston at

80

that end of the cylinder in advance of the piston in its movement and at which the said initial proportion has taken place, the mo-

85

tive fluid will enter against partially-compressed air, and will hence not only fill the cylinder-space quicker, but a smaller quantity of motive fluid will be required to so fill it than if the motive fluid were to enter against

90

free and uncompressed air.

In a series of tests which I have made I have found a very high degree of economy coupled with a very great efficiency has resulted from the arrangement and proportion

95

herein described, shown, and claimed.

What I claim is—

1. In a valveless rock-drill, the combination with a cylinder having separate admission and exhaust ports for each end of the cylinder and

95

a common inlet-port, of a piston, having a reduced central portion and adapted to control the said ports, the said ports being so located with respect to each other and to the piston that during a rearward stroke of the piston,

100

admission cut-off at the forward end is substantially simultaneous with exhaust-closure at the rear end but is earlier with respect to a full stroke of the piston than the corresponding point of admission cut-off at the rear end

105

during a forward stroke.

2. In a valveless rock-drill, the combination with a cylinder having separate admission and exhaust ports for each end of the cylinder, and

110

a common inlet-port, of a piston, having a reduced central portion and adapted to control the said ports, the said ports being so located with respect to each other and to the piston, that during a rearward stroke of the piston, release at the forward end is substantially si-

115

multaneous with admission at the rear end but is earlier with respect to a full stroke of the piston than the corresponding point of release at the rear end during a forward stroke.

3. In a valveless rock-drill, the combination with a cylinder having separate admission and exhaust ports for each end of the cylinder, and

120

a common inlet-port, of a piston, having a reduced central portion and adapted to control the said ports, the said ports being so located with respect to each other and to the piston that during a rearward stroke of the piston,

125

admission cut-off and release at the forward end are respectively substantially simultaneous with exhaust-closure and admission at the rear end but are respectively earlier with respect to a full stroke of the piston than the

130

corresponding points of admission cut-off and release at the rear end during a forward stroke.

4. In a valveless rock-drill, the combination 5 with a cylinder having separate admission and exhaust ports for each end of the cylinder, and a common inlet-port, of a piston, having a reduced central portion and adapted to control the said ports, the said ports being so located 10 with respect to each other and to the piston that during a rearward stroke of the piston, exhaust-closure at rear end is substantially simultaneous with admission cut-off at the forward end but is prior to exhaust-release 15 thereat.

5. In a valveless rock-drill, the combination 20 with a cylinder having separate admission and exhaust ports for each end of the cylinder, and a common inlet-port, of a piston, having a reduced central portion and adapted to control the said ports, the said ports being so located 25 with respect to each other and to the piston, that during a rearward stroke of the piston, release at the forward end is substantially simultaneous with admission at the rear end but is subsequent to exhaust-closure thereat.

6. In a valveless rock-drill, the combination 30 with a cylinder having separate admission and exhaust ports for each end of the cylinder, and a common inlet-port, of a piston, having a reduced central portion and adapted to control the said ports, the said ports being so located 35 with respect to each other and to the piston, that during a rearward stroke of the piston, exhaust closure and admission at the rear end are respectively substantially simultaneous 40 with admission cut-off and release at the forward end but that exhaust-closure, forward of the piston in its movement in either direction, takes place prior to exhaust-release rearward thereof.

7. In a valveless rock-drill, the combination 45 with a cylinder, having separate admission and exhaust ports for each end of the cylinder, and a common inlet-port, of a piston, having a reduced central portion and adapted to control the said ports, the said ports being so located 50 with respect to each other and to the piston that the expansion of working fluid at the forward end of the cylinder takes place while, and only while, the rear end of the cylinder is closed to both admission and exhaust, but that the expansion period is later, with 55 respect to a full stroke of the piston, during a forward stroke than during a rearward stroke.

8. In a valveless rock-drill, the combination 60 with a cylinder having separate admission and exhaust ports for each end of the cylinder, and a common inlet-port, of a piston, having a reduced central portion and adapted to control the said ports, the said ports being so located 65 with respect to each other and to the piston, that the expansion of the working fluid at the rear end of the cylinder takes place while, and only while, the forward end of the cylinder is closed to both admission and exhaust, but that the expansion period is later, with

respect to a full stroke of the piston, during a forward stroke than during a rearward stroke.

9. In a valveless rock-drill, the combination 70 with a cylinder having separate admission and exhaust ports for each end of the cylinder, and a common inlet-port, of a piston, having a reduced central portion and adapted to control the said ports, the said ports being so located 75 with respect to each other and to the piston that the expansion of working fluid at either end of the cylinder takes place while, and only while, the other end of the cylinder is closed to both admission and exhaust, but that the expansion period is later, with respect to 80 a full stroke of the piston, during a forward stroke than during a rearward stroke.

10. In a valveless rock-drill, the combination 85 with a cylinder having separate admission and exhaust ports for each end of the cylinder, and a common inlet-port, of a piston, having a reduced central portion and adapted to control the said ports, the said ports being 90 so located with respect to each other and to the piston that the expansion period of a stroke in either direction is substantially equal, but is later with respect to a full stroke of the piston, during a forward stroke than during a stroke in the rearward direction. 95

11. In a valveless rock-drill, the combination 100 with a cylinder having separate admission and exhaust ports for each end of the cylinder, and a common inlet-port, of a piston, having a reduced central portion and adapted 105 to control the said ports, the said ports being so located with respect to each other and to the piston, that the distance traveled by the piston up to the point of admission cut-off, during a full stroke in either direction, is substantially equal to the distance traveled by the piston during exhaust period in a full stroke in the other direction, but is substantially 110 twice as great during a full stroke in the forward direction, as during a full stroke in the rearward direction.

12. In a valveless rock-drill, the combination 115 with a cylinder having separate admission and exhaust ports for each end of the cylinder, and a common inlet-port, of a piston, having a reduced central portion and adapted to control the said ports, the said ports being 120 so located with respect to each other and to the piston, that the expansion period of a stroke in either direction is substantially equal, the distance traveled by the piston up to the point of admission cut-off, during a full stroke in one direction, being substantially 125 equal to the distance traveled by the piston during exhaust period in a full stroke in the other direction, but substantially twice as great during a full stroke in the forward direction, as during a full stroke in the rearward direction.

13. In a valveless rock-drill, the combination 130 with a cylinder having separate admission and exhaust ports for each end of the cylinder, and a common inlet-port, of a piston, having a reduced central portion and adapted

to control the said ports, the said ports being so located with respect to each other and to the piston, that the expansion period of a stroke in either direction is about equal to 5 one-fifth of a full stroke, and that the distance traveled by the piston up to the point of admission cut-off, during a full stroke in one direction, is substantially equal to the distance traveled by the piston during exhaust period in a full stroke in the other direction, to but is substantially twice as great during a full stroke in the forward direction, as during a full stroke in the rearward direction.
